UNITED STATES PATENT OFFICE.

GEORGE A. JOHNSON, OF CHICAGO, ILLINOIS, ASSIGNOR TO WILLIAM H. MINER, OF CHAZY, NEW YORK.

ROLLER-BEARING.

1,290,215.

Specification of Letters Patent. Patented Jan. 7, 1919.

Application filed February 16, 1918. Serial No. 217,520.

To all whom it may concern:

Be it known that I, GEORGE A. JOHNSON, a citizen of the United States, residing at Chicago, in the county of Cook and State 5 of Illinois, have invented a certain new and useful Improvement in Roller-Bearings, of which the following is a full, clear, concise, and exact description, reference being had to the accompanying drawings, forming a part 10 of this specification.

This invention relates to improvements in roller bearings.

In the operation of rolling stock and more particularly steam roads, it is customary to 15 provide anti-friction roller side bearings between the truck and body bolsters of the cars to minimize the friction when the trucks swivel or swing relatively to the car bodies as the cars pass over curved portions of the 20 tracks, and for the further purpose of preventing undue tilting or swaying of the car bodies when the cars strike a curve or pass from a curve to a tangent. Due to the wear on the engaging parts of the body and truck 25 bolsters of the cars and also due to distortion which sometimes occurs, it has been found necessary or desirable in a great many instances to provide means in the roller side bearings to compensate for the changing 30 conditions resulting from the wear or distortion above mentioned. Heretofore, so far as I am aware, the general practice in thus compensating for the variable conditions mentioned, has been to mount the anti-friction 35 roller or rollers either in a cradle or an equivalent manner in such a way that the roller could adjust itself bodily about an axis transverse to the bolster on which it is mounted. As will be apparent, this involves 40 extra parts with consequent increased cost of manufacture.

An object of my invention is to provide an anti-friction roller suitable for side bearings of railway cars, which consists of a 45 minimum number of parts and wherein means are provided for compensating for the variable conditions above indicated without employing any rockable or adjustable mounting for the anti-friction roller.

Another and more specific object of the 50 invention, is to provide a roller side bearing for railway cars wherein the roller is rotatable about a relatively fixed axis and which is so designed to coöperate with a bearing 55 plate on the opposed bolster that variations

in the relation of the opposed bolsters will be accommodated by the roller bearing without necessitating any adjustment of the anti-friction roller itself.

In the drawings forming a part of this 60 specification, Figure 1 is a vertical, sectional view, taken transversely of the body and truck bolsters of a railway car showing my improvements in connection therewith. Fig. 2 is a vertical sectional view, taken substantially on the line 2—2 of Fig. 1. And Fig. 3 is a bottom plan view of the upper bearing plate employed with my improved side bearing.

In said drawing, 10 denotes the bottom 70 wall of a body bolster of a car and 11 the upper wall of a truck bolster. The improved side bearing includes a base casting A; an anti-friction roller B; and a coöperating bearing plate C.

The base casting A, as shown, is in the 75 form of a hollow rectangular box or frame having a lower wall 12 provided with suitable flanges 13 by which it can be riveted to the truck bolster; upwardly extending end 80 walls 14—14 suitably recessed at the bottom, as indicated at 15, to permit dirt and other foreign matter to be washed out; and parallel side walls 16—16.

The anti-friction roller B has its bearing 85 surface convex, as indicated at 17, the roller B being mounted on a fixed axle or journal 18 supported in the side walls 16—16 of the casting A, said axle 18 being held against accidental displacement by any suitable 90 means, such as a cotter 19 carried by a pair of laterally extended ears 20—20 on one side of the casting A.

The bearing plate C is also preferably in 95 the form of a casting adapted to be riveted to the upper or body bolster 10, said bearing plate C having end lugs 21—21 by which it may be so riveted. The bearing plate C is curved lengthwise, as clearly indicated in Fig. 3, on a radius corresponding to the 100 distance from said bearing plate to the kingpin by which the body and truck bolsters are usually connected. On its under face, the bearing plate C is made concave as clearly indicated at 22 in Fig. 2, the radius 105 of said concave surface 22 being the same as the radius defining the convex bearing surface 17 of the roller B.

In normal position of the parts, there is 110 a slight space left between the roller B and

the bearing plate C, as clearly illustrated in Fig. 2. When the two bolsters approach each other due to the car changing its direction of motion or as the car body sways, it is evident that the roller and bearing plate C will come into engagement, and due to the fact that the bearing surfaces of the roller and plate are struck with equal radii, there will be complete contact between the 10 roller and the bearing plate for the full width of the roller. The length (not the radius) of the arc of the concave bearing surface 22 is somewhat greater than the length (not the radius) of the arc of the bearing surface 17 of the roller so that, as the angular relation between the bolsters 10 and 11 varies due to wear or distortion of any of the car parts, there will also remain a full contact between the roller and the 20 bearing plate C, the action being the same as though the bearing plate C were fitted on the roller B and shifted thereon about a horizontal axis perpendicular to the axis of the axle 18. In this manner, I obtain the 25 same effect as is obtained by those roller side bearings now on the market which employ a rockable cradle or mounting for the anti-friction roller, and it is obvious that my structure is much simpler, comprises 30 fewer parts, less likely to get out of order, and is much cheaper both in first cost and in maintenance.

Although I have herein shown and described what I now consider the preferred 35 manner of carrying out the invention, the same is merely illustrative and I contemplate all changes and modifications that come within the scope of the claims appended hereto.

40 I claim:

1. In a roller bearing adapted for use between two members relatively rockably mounted; the combination with a retaining casting in which said roller is rotatably 45 mounted, said retaining casting being adapted to be secured to one of said members; and a bearing surface on the other of said members, said bearing surface being curved about the same axis as that about which the two 50 members are adapted to rotate relatively,

said bearing surface for the coöperating engaging surface of the roller being complementally curved in transverse section to thereby insure full contact between the roller and the bearing surface. 55

2. In a roller bearing adapted to be mounted between the body and truck bolsters of a car; the combination with a retaining member adapted to be secured to one of said bolsters; of an anti-friction roller 60 rotatably mounted in said retaining member about a relatively fixed axis, said roller having a bearing surface curved transversely thereof; and a bearing surface on the other of said bolsters, said bearing surface being 65 curved transversely thereof to correspond with and fit the bearing surface of said roller.

3. In a roller bearing adapted for use between body and truck bolsters of a car; the 70 combination with a retaining member adapted to be secured to one of said bolsters; an anti-friction roller rotatably mounted in said retaining member about a relatively fixed axis, said roller having the bearing 75 surface thereof convexed transversely; of a bearing surface on the other of said bolsters, said bearing surface being concaved transversely and adapted to fit said convex surface of the roller. 80

4. In a roller side bearing for railway cars, the combination with a base casting adapted to be secured to one of the car bolsters; of an anti-friction roller rotatably mounted in said base casting about a relatively fixed axis, said roller having the bearing surface convexed transversely thereof; of a bearing plate adapted to be secured to the opposed car bolster, said bearing plate being curved longitudinally on a radius corresponding to the distance from said bearing plate to the pivotal connection of the car bolsters, said bearing plate being also curved transversely thereof to fit said curved bearing surface of the roller. 95

In witness that I claim the foregoing I have hereunto subscribed my name this 7th day of Feb., 1918.

GEORGE A. JOHNSON.
